BREECH MECHANISM FOR AUTOMATIC FIREARMS

Friedrich Linder, Zurich, Switzerland, assignor to Machine Tool Works Oerlikon, Administration Company, Zurich-Oerlikon, Switzerland, a company of Switzerland

Filed Feb. 3, 1958, Ser. No. 712,813

Claims priority, application Switzerland Feb. 7, 1957

1 Claim. (Cl. 89—183)

The present invention relates to a breech mechanism for automatic firearms, and has the primary objects of providing a breech mechanism in which the inertia mass is divided into two parts, the rear part of which is accelerated at a higher rate than the forward part, resulting in a smaller total inertia mass than in pure breech mass locked breech mechanisms and dispensing with a gas drive therefor, and at the same time providing a safe abutment for the bottom of the cartridge when fired. It is another important object of the invention to provide a breech mechanism of the kind referred to, wherein the locking of the breech is abolished at the moment only, when the projectile has left the barrel and the pressure in the barrel has dropped to a value which does not mean any more danger to the cartridge case. It is yet another important object of the invention to provide a breech mechanism of the kind referred to which is suitable also for medium and large caliber automatic weapons.

With these and other objects in view, I provide a breech mechanism for automatic fire arms, comprising in combination: a barrel, a breech head taking the thrust of the bottom of the cartridge fired, a rear breech portion, locking means therefor, said rear portion being slidably longitudinally and the said locking means being moveable transversely of the axis of the said barrel, and a locking tongue extending axially from the said rear portion towards said breech head and engaging with play said locking means, said breech head bearing through said locking means on roof-like inclined faces stationary relative said barrel and on inclined faces directed transversely thereof on said rear portion, whereby said breech head when recoiling accelerates said rear portion at an increased ratio, said locking means after initial transverse movement owing to backsiding of the said breech head, is locked during part of the rearward movement of the said rear portion and thereby in turn interlocks the said breech head rigidly with the said barrel.

A breech mechanism according to the invention is not affected by the unavoidable fluctuations in the pressure rise within the cartridge in the course of time after priming. It is also safeguarded against rebound phenomena occurring in the breech which in known breech mechanisms did not provide with certainty that the components of the breech are at the moment of the shot development at a completely closed position and at rest. This danger may be countered by rebound-preventing means, which however in their known embodiments are only rebound-damping or rebound-delaying devices by which the element of danger set forth hereinabove is only reduced but not completely eliminated.

This uncertainty, which is disquieting to the gunner, was also the reason why one had not yet dared to provide automatic weapons of medium or large caliber with such known breech mechanisms. With ammunition of small caliber weapons delayed burning after priming oc-

2

curs to a far lesser extent than with larger calibers, since the priming charge ignites the comparatively small charge at once and uniformly. However, the larger the charge, the more uneven the ignition thereof and the higher the danger of burst cartridge cases.

These difficulties have been successfully overcome by the present invention. In order that the same and its various details and features may be clearly understood and readily carried into effect, two embodiments thereof will now be described by way of example with reference to the accompanying drawings, in which for clarity only those components are illustrated, which are essential for the understanding of the invention, and wherein:

Fig. 1 is a vertical section of a breech according to the invention.

Fig. 2 is a horizontal section of a first embodiment of the breech locked by means of abutment flaps, in the priming position,

Fig. 3 shows the breech according to Fig. 2 in the condition of the breech head being rigidly interlocked,

Fig. 4 shows the breech completely unlocked, and

Fig. 5 is a horizontal section of another embodiment of the breech, in which the locking is effected by means of slider blocks.

The breech according to Fig. 2 is accommodated in a casing 10, in which the barrel 1 is rigidly mounted, and the breech head 2 as well as the rear portion 4 of the breech are mounted longitudinally slidably. A closure spring 6, which is arranged pre-loaded between a breech cover 13 screwed to the casing 10 and the rear portion 4 of the breech, forces the breech as a whole into the priming position shown in Figs. 1 and 2. On the breech head 2 an extractor 3 is fixed and in the locking tongue 9 of the rear portion 4 of the breech a percussion pin 5 is pivoted by means of a pin 14, said percussion pin reaching through a bore 15 of the breech head 2. The rear portion 4 of the breech transmits the pressure through the face 4d on to the breech head 2, which in the priming position abuts in turn the faces 10b of the casing 10. Rearwardly the breech head 2 bears through two abutment flaps 8 on inclined faces 10a of the casing 10. These abutment flaps 8 are forced by the inclined faces 4a of the rear portion 4 of the breech into a swung-out position (conf. Fig. 2). A cartridge casing 11 inserted into the barrel 1 bears on the face 2a of the breech head. The sear 7 serves in the usual manner for retaining the breech in the cocked position in that it abuts the inclined face 4e of the rear portion 4 of the breech.

The manner of functioning of the breech mechanism is as follows:

After actuation of the sear 7 the closure spring 6 drives the breech as a whole forward to the battery position, in which the breech head 2 abuts the faces 10b.

The percussion pin 5 thereby primes the cartridge 11 in the usual manner, whereafter the cartridge casing forces the breech head 2 rearward. This thrust is transmitted by the abutment flaps 8 to the inclined faces 10a on the casing 10, and since these inclined faces are not self-locking and the faces of the flaps 8 opposite to the faces 4b of the locking tongue 9 do not contact these latter faces but stand at a distance from them, the abutment flaps 8 will tend to give way inwardly. In this way, in the battery position there is no positive locking of the breech head; the locking action is assumed only by the combined mass of the two breech portions 2 and 4. By the inward movement of the abutment flaps 8 they impart to the rear portion 4 of the breech through the inclined faces 4a of the latter a rearward acceleration, until the abutment flaps 8 in an intermediate position come into contact with the two parallel faces 4b of the lock-

70

ing tongue 9 of the rear portion 4 of the breech while still contacting the faces 10a (see Fig. 3). During this operation the breech head 2 has moved rearward a short stretch but is restrained from further movement by the abutment flaps contacting the two parallel faces 4b of the locking tongue 9. The breech head is thereby positively locked.

The rear portion 4 of the breech continues its movement owing to its inherent kinetic energy, until the support of the abutment flaps by the two parallel faces 4b of the locking tongue 9 at its forward end is abolished and the abutment flaps 8 under the influence of the thrust of the fired cartridge swing further inwardly, whereby the positive locking of the breech head is abolished. The breech components then assume the unlocked position of Fig. 4. The rear portion 4 of the breech, by the abutment face 4c then carries along also the breech head, the return movement of the rear portion of the breech and of the breech head in unison being effectively assisted by the remainder of the gases in the barrel.

During the recoil of the breech the spent cartridge case is ejected in the usual manner by the ejector 3 from the barrel, and the closure spring 6 is loaded, which after the rear reversal of the breech throws the same again forward, whereby a new cartridge is supplied from the magazine or belt. After the breech head 2 having abutted the faces 10b of the casing, the locking of the breech is effected in the reverse sequence of the unlocking thereof. The inclined faces 4f (Fig. 4) of the locking tongue 9 spread the abutment flaps 8 out, so that the same assume again their original locking position.

Instead of the locking flaps 8 shown in the Figs. 2 to 4 serving as locking means the supporting of the breech head against the weapon casing may alternatively be effected by locking means of a different kind, such as for example by the slider blocks 12 shown in Fig. 5. The manner of functioning of these slider blocks corresponds exactly to that of the abutment flaps 8 of the Figs. 2 to 4.

The embodiments illustrated show the breeches each having two locking means 8 or 12, respectively. Nothing would be changed in the substance of the invention if only one such locking means were used. Likewise it is possible to build in more such locking means, for example three or even four of them.

Other obvious modifications may occur to a person skilled in the art, and I wish to be understood that I do not limit myself to the particular details and dimensions of the preferred embodiments herein described and illustrated.

What I claim as my invention and desire to secure by Letters Patent, is:

A breech mechanism for an automatic firearm, comprising in combination a receiver substantially extending along a longitudinal axis of said firearm, said receiver comprising a first abutment face inclined to said axis; a two-part breech block movably guided in said receiver, including a breech head loaded by the rearward thrust of a fired cartridge and reciprocable between a battery breech mass lock position, a recoiled position and an intermediate positive lock position, said breech block further including a rear breech portion comprising a second abutment face inclined to said axis and a locking tongue with a forward end, said tongue extending axially from said further abutment face toward said breech head; a recoil spring engaging said rear breech portion to bias said breech block toward the said battery breech mass lock position; locking means movably arranged in said receiver and engaging said breech head, said locking means in said battery breech mass locking position being spaced from said locking tongue and simultaneously engaging both said abutment faces, said locking means in said intermediate positive lock position further simultaneously engaging said first named abutment face and said tongue, said locking means upon a rearward movement of said breech head out of said battery breech mass locking position caused by the thrust of a fired cartridge effecting a sliding movement along said first abutment face towards said intermediate, positively locked position, thereby diminishing said spacing, and simultaneously effecting a further sliding movement along said second abutment face to impart a recoiling movement to said rear breech portion; said locking means sliding during said recoiling movement along said tongue up to said forward end and thereupon becoming disengaged from said tongue, and said locking means upon reaching said forward end of said tongue under the influence of the thrust of a fired cartridge becoming disengaged from said first abutment face thereby to unlock said breech head.
